UNITED STATES PATENT OFFICE.

GEORGE C. DEVED AND GARRETT F. DEVED, OF BALTIMORE, MARYLAND.

CORE BOX.

Application filed September 8, 1921. Serial No. 499,170.

To all whom it may concern:

Be it known that we, GEORGE C. DEVED and GARRETT F. DEVED, citizens of the United States of America, both residing in the city 5 of Baltimore, State of Maryland, have invented certain new and useful Improvements in Core Boxes, of which the following is a specification.

The present invention relates to an improved core box for making window weight cores, the broad features of which are disclosed and claimed in patent of Smith B. and George C. Deved, No. 1,387,531. The patented core box embodies as one of its 15 important features, a removable number located between upright projections or legs near the bottom of the core chamber. These projections with the cross arm or rod which rests on the top ends of the projections are reproduced in the casting as the upper end 20 of the sash weight the cross arm and projections forming the eye in the sash weight and the removable number likewise reproduced appears in a prominent position on 25 the casting, i. e., at the bottom of the eye indicating the weight of the casting.

The removable number combined with the other features which give great speed of operation, makes it possible and feasible to 30 produce the cores for all the sash weights of all the different sizes made in the average foundry by means of a single core box. The removable number in the patented core box is carried on a clip or plate which is placed 35 or hooked between the projections or legs. While this is a perfectly practical operative device, the ends of the plate become worn and the plate is more or less apt to be displaced while the core box is in use.

40 The present invention includes as one of its features, a number plate which is mounted on a central pin or spindle which fits down in a corresponding socket in the box. The projections between which the number 45 plate fits and the pin and socket hold the number plate in position so that it cannot by any chance become displaced unless it is intentionally removed, which is of course necessary in changing from one size of 50 weights to another.

An important feature of the patented core box resides in the structure which includes two swinging sides having registering concavities, forming the core pockets and a base 55 on which the sides are pivoted to swing tongue-wise and a rod which forms the tops of

the eyes in the weights by first forming eyes in the cores, which rod extends through the box longitudinally and parallel to the axis of swing being seated in other registering 60 concavities in the meeting surfaces of the sides. This arrangement has resulted in a core box which turns out cores at a greatly increased speed as compared to the previous practice in this line.

65 The present invention relates to this type of box and contributes to a further increase in the speed of operation. The previous core boxes which were made to open and shut in this manner have been fastened by 70 means of a pivoted bolt having a wing nut, the bolt being pivoted to one side of the core box and the swinging end of the bolt dropping into a notch on the other side so that the wing nut could be tightened against 75 the notched member to draw the tops of the box together. This is effective as a fastening but to open it requires several seconds at each end of the operation, i. e., when the box is closed and when it is opened. The present 80 invention provides a fastening device which is thrown open by a single motion and in closing requires no attention at all, dropping into position as the box is closed and locking by gravity with sufficient security for ordinary purposes, though it may be further tightened.

85 In the accompanying drawing we have illustrated a core box provided with the features of our invention.

90 In the drawing:

Figure 1 is a plan of the box closed and locked.

Figure 2 is a reduced end view showing the box closed but unlocked.

95 Figure 3 is a transverse section on the line 3—3, Figure 1, showing the box closed and locked and containing a core print.

Figure 4 is an end view of the box closed.

Figure 5 is a side view of the box looking 100 from the left in Figure 3, showing the box closed and locked and broken away to show a pocket.

Figure 6 is a perspective view of a core print.

105 Figure 7 shows the upper end of a sash weight with the eye and number, the same being of the type produced from the core made from the applicant's box.

Figure 8 is a side view of the core box 110 partly broken away to show the improved number plate.

Figure 9 is a transverse section on the line 9—9 of Figure 8, showing our improved number plate.

Figure 10 is a plan of the box broken 5 away.

Figure 11 is an elevation of the improved number plate.

Figure 12 is a plan of the same.

Referring to the drawings by numerals, 10 the core box consists of side members, 1 and 2, and a bottom member 3, the side members being pivoted at 4 and 5 to the bottom member to swing tongwise relatively thereto. The side members are provided with 15 corresponding registering apertures or concavities 6—7, which when the box is closed, form the pockets in which the cores or core prints are shaped. These holes are closed by the bottom member which preferably has 20 upright protuberances 8, and in the form of the invention shown the protuberances are provided with projections 9—9 spaced apart to form the eye 10, which is closed at the top by a longitudinal rod 11, parallel to 25 the axes of swing of the side members, i. e., pivots 4, 5, passing through the entire box which may have as many pockets or apertures as desired. The meeting surfaces of the swinging members 1 and 2 are hollowed 30 out in suitable registering concavities 12—12' to receive the rod.

In accordance with our invention a removable plate 15 is supported on the plug between the legs and removably secured 35 thereto. In the present instance, the number plate is concaved as to its sides 16—17 to fit the projections 9—9, and is provided with a downwardly projecting pin 18 to fit in a socket or hole 19 in the bottom of the 40 pocket. In this way the plate is held securely in position so long as desired and is conveniently removed at will. The security afforded being such however, as to eliminate any chance of the plates being accidentally 45 removed or displaced.

Figures 1, 2 and 3 are particularly illustrative of the fastening. It consists of a transverse swinging locking arm 20, pivoted to one side of the box at the top at 21 50 and having a rearwardly projecting stop 22, integral with the arm and projecting on the opposite side of the pivot therefrom. At the swinging end the arm is provided with a head 23, to which is pivoted an eccentric 55 24, having an eccentric arm 25 rigidly secured thereto, the arm being as shown substantially at right angles to the greatest radius of the eccentric.

The box is shown fastened in Figure 3. 60 To unfasten and open it the arm 25, is thrown up and the locking arm thrown back as seen in Figure 2, until the stop 22 rests against the side of the box. In this position the center of gravity of the arm has 65 swung by the center of the pivot 22 so that

it is in stable equilibrium. The box may now be opened and the core removed, after which the box is preferably swung sharply to closed position which causes the locking arm 20 with the eccentric arm 25 carrying the eccentric 70 24 to swing forward and drop so that the arm 20 rests on the box, in the form shown, lying in the notch 26. As the arm 20 falls the eccentric arm 25 swings forward and downward rotating the eccentric 75 and with a cam action tightening the fastening until the resistance overcomes gravity and the acceleration thus acquired. The weight of arm 25 locks the box by rotating the eccentric and tends to hold the eccentric 80 in locked position.

It is obvious that the operation described, even though it should be necessary to apply slight pressure to the arm 25, to complete the fastening operation, is very much quicker 85 than any of the known screw type of core box fastenings and that it lends itself to the most efficient operation of the box, and further that it corresponds to the rest of the apparatus in that it may be operated to great 90 advantage by the most unskilled labor.

We have thus described specifically and in detail a single embodiment of our invention so that the nature and operation of same may be clearly understood, however, the 95 specific terms herein are used descriptively rather than in a limiting sense, the scope of the invention being defined in the claims.

What we claim and desire to secure by 100 Letters Patent is:

1. A core box consisting of tongwise swinging members having registering concavities forming a core pocket, a base closing the bottom of the pocket, members projecting into the pocket at the sides and a removable number plate fitting between the projections and provided with a pin, the base having a socket to receive the pin. 105

2. A core box for window sash weights 110 adapted to produce eye forming cores consisting of laterally swinging members having registering concavities to form the core pockets, a base closing the bottom of the pockets and having upwardly projecting legs and a bar resting on the legs, the eyes and a removable number plate for each pocket fitting the space between the legs, and having a downwardly projecting pin, the base having a socket to receive the pin. 115

3. A core box for producing eye forming cores for sash weights, the core box having tongwise swinging side members with registering concavities forming the core pockets, fastening means for the swinging members 125 consisting of an arm pivoted near the top of one side member to swing in a transverse plane and having a rearwardly projecting stop adapted to support the arm when it swings backward past the vertical and cam 130

member pivoted on the swinging end of the arm so as to engage the other swinging member on the side remote from the first mentioned pivot, the cam member having an arm 5 projecting therefrom by which it may be rotated.

4. A core box for producing eye forming cores for sash weights, the core box having 10 tongwise swinging side members mounted thereon with registering concavities forming the core pockets, fastening means for the swinging members consisting of an arm pivoted to one side member to swing in a transverse plane and having a stop adapted 15 to support the arm when it swings backward past the vertical end, an eccentric

member pivoted on the swinging end of the arm so as to engage the other swinging member on the side removed from the first mentioned pivot, the eccentric member 20 having an arm projecting therefrom by which it may be rotated, the eccentric arm being substantially at right angles to the longest radius of the eccentric.

Signed at Baltimore, Maryland, this 1st 25 day of September, 1921.

GEORGE C. DEVED.
